UNITED STATES PATENT OFFICE.

ALBERT E. JONES, OF EAST ORANGE, NEW JERSEY.

TRACING OR MARKING TOOL.

No. 846,569.

Specification of Letters Patent.

Patented March 12, 1907.

Application filed March 7, 1906. Serial No. 304,698.

To all whom it may concern:

Be it known that I, ALBERT E. JONES, a citizen of the United States, residing at East Orange, in the county of Essex and State of New Jersey, have invented certain new and useful Improvements in Tracing or Marking Tools; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has reference generally to improvements in markers or gages used in the arts by carpenters, machinists, or the like; and my present invention has reference more particularly to a novel tracing or marking implement or gage having a number of tracers or markers variously disposed in different sides or faces of the tool or implement, the same being arranged that one or more clearly-defined lines or marks may be produced upon a piece of wood or other article on the same or on different faces of the article which is to be marked.

The invention, therefore, has for its principal object to provide a simply-constructed and cheaply-made marking or tracing tool or implement which can be easily manipulated for marking or tracing one or more lines upon one or two of the faces of the article which is to be traced or marked, all with a view of providing a gage or marking implement or tool which may be used as an ordinary gage or marker, but which is primarily adapted for use as a door-butt gage for marking a door and door-frame at the points where the wood is to be cut away for the reception of the respective leaves of the door-hinges.

A further object of this invention is to provide a tracing or marking implement or tool of the general character hereinabove set forth which may be used to mark the width and depth of a rabbet and may also be used for marking or tracing parallel lines upon a surface when it is desired to produce a mortise or groove or the like in the surface of the piece of material which has been marked.

A further object of this invention is to provide a marker or tracing implement or tool comprising a main body having guiding edges, the said body being provided with a plurality of guiding holes, in each one of which a stem or rod carrying a tracing or

marking wheel or disk is adjustably secured and may be removably secured, as will hereinafter more fully appear.

Other objects of this invention not at this time more particularly mentioned will be clearly understood from the following detailed description of the tracing or marking tool, gage, or implement.

This invention is clearly illustrated in the accompanying drawings, in which—

Figures 1 and 2 are two horizontal sectional representations of a door-frame and two styles of doors in their relative positions in said door-frames before being hung by means of the usual hinges, the said views showing an arrangement of traces or marks made with the tool or implement embodying the principles of the present invention. Fig. 3 is a horizontal section of the door-frame shown in said Fig. 1 and an end elevation of the marking tool or implement, showing the same in its relative position against the edge of the door-frame for producing the traces or marks illustrated upon the door-frame in said Fig. 1; and Fig. 4 is a similar view of a portion of the door shown in said Fig. 1 and an elevation of the opposite end of the marking tool or implement, showing the same in its relative position against the edge of the door for producing the traces or marks illustrated upon the door in said Fig. 1. Figs. 5 and 6, respectively, are views similar to those represented in said Figs. 3 and 4, illustrating the use of the tracing or marking implement or gage with the door-frame and the door represented in said Fig. 2 of the drawings. Fig. 7 is a face view of the tool or implement, and Fig. 8 is a face view of the device looking in the direction of the arrow Y in said Fig. 7. Fig. 9 is a sectional representation of the device, said section being taken on line 9 9 in said Fig. 8; and Fig. 10 is a transverse section taken on line 10 10 in Fig. 7. Fig. 11 is a detail sectional representation of one of the tracer or marker rods and its tracing-wheel or marker, said view illustrating one arrangement of rotatively securing said wheel or marker upon the end of said rod.

Similar characters of reference are employed in all of the said above-described views to indicate corresponding parts.

Referring now to said figures of the drawings, the reference-character 1 indicates the complete tracing or marking tool or implement or gage, the same comprising a suitably-formed body of metal or other suitable

material having a wide portion 2 and a narrow portion 3, said portions being integrally united and having angular guide portions 4 and 5 between them, substantially as illustrated in the several figures of the drawings and for the purposes hereinafter more fully set forth. Extending directly through the said wide and narrow portions 2 and 3 of the said body are a pair of tubular guiding-holes 6 and 7, a cylindrical rod 8 being slidably arranged in the hole 6 and a cylindrical rod 9 being slidably arranged in the hole 7, the said rods extending or projecting from the opposite faces of the said body, as shown. The said rod 8 is provided upon its one end with a tracer or marker wheel or disk 10, and likewise the said rod 9 is provided at its one end with a tracer or marker wheel or disk 11. The said marker wheels or disks 10 and 11 are respectively formed with sharp marginal tracing or marking edges 12 and 13, substantially of the form shown. The said bars or rods 8 and 9 are slidably and reversably arranged in their guiding holes 6 and 7 and are secured in their adjusted and fixed relation within the said holes by means of suitable retaining means. The preferred retaining means or devices which I desire to use are a set-screw 14, which is arranged in a screw-threaded hole 15 in the part 2, said screw 14 being provided with a head or finger piece 16 for screwing the opposite end portion of the said screw 14 against and in binding relation with the side of the cylindrical rod 8, and a set-screw 71, which is arranged in a screw-threaded hole 18 in the part 3, said screw 17 being provided with a head or finger piece 19 for screwing the opposite end portion of said screw 17 against and in binding relation with the side of the cylindrical rod 9. That the marginal tracing or marking edges 12 and 13 of the respective tracing or marking wheels or disks 10 and 11 will respectively extend beyond the edges 20 and 21 of the narrow part 3 of the body of the device, so that when using the one marker or tracing wheel or disk the other marker or tracing wheel or disk will not produce a line also, the said two rods 8 and 9 and their wheels or disks 10 and 11 are set out of vertical alinement, as clearly shown in the several figures of the drawings and the purposes of which will be clearly evident. The said portion 2 is also provided with a laterally-extending guiding-hole 22 and an enlarged recessed portion 23, a cylindrical rod 24 being slidably arranged in said hole 22, having one of its ends extending from one face of said part 2 and the other end of said rod 24 extending into and through said recessed portion 23 and being provided upon said end with a marker or tracing wheel or disk 25, which is provided with a sharp tracing or marking edge 26, substantially as illustrated. To retain the said rod 24 in its adjusted and fixed position, the said

portion 2 is provided with a screw-threaded hole 27, into which is screwed a set-screw 28, provided with a head or finger piece 29, by mean sof which the opposite end of said screw can be brought into its holding or binding relation with the side of said rod 24, as clearly illustrated. One method of rotatably securing the said marking or tracing wheels or disks 10, 11, and 25 to their respective rods 8, 9, and 24 is clearly indicated in Fig. 11 of 75 the drawings, in which drawing I have represented for illustration the rod 8 and its wheel or disk 10. As shown in said Fig. 11, the rod 8 is made with a screw-threaded receiving-socket 30 and a reduced portion 31, 80 upon which the wheel or disk is rotatably arranged. The said wheel or disk is secured in its rolling relation upon said reduced portion 31 by means of a screw 32, the head 33 of which rests within a centrally-disposed 85 recess 34 in the face of the tracing or marking disk or wheel 12, so that the face of the said head and the face of the wheel are flush, or substantially so, as shown. The purpose of this will be clearly evident, more particularly from an inspection of Fig. 3, and is to enable the operator to use the device for tracing or marking purposes with a rabbet or closely against a projecting member extending from the face of the main body portion 90 upon which a mark or marks are to be produced. As an illustration of using the tracing or marking tool or implement, it will be necessary to refer to Figs. 1 to 6, inclusive, of the drawings. In Figs. 1, 3, and 4 I have represented the use of the device for rapidly laying out the marks to which parts of the door-frame and a door are to be cut away for the reception of the leaves of the hinges. Referring now to the said figures of the drawings, the reference character 35 indicates a portion of the door-frame, and 36 is the door which in this instance is to be hung in the door-frame with its face 37 flush with the 100 face portion 38 of the frame 35. After having laid out the distances from the top and bottom edges, respectively, of the door-frame and door the rod 8, with its tracing or marking disk or wheel 11, is secured in the adjusted position, (indicated in Figs. 3 and 4,) 105 as shown, and the rod 24 and its tracing-wheel 25 are likewise secured in their adjusted positions, the various parts having been secured in their variously-adjusted positions 110 according to the kind and sizes of the hinge-leaves which are to be let in the wood. The body of the tool or implement is placed with its guiding edge 5 against the edge 39 of the frame 35 in the manner indicated in Fig. 3, 115 and by drawing the tool along the said edge the tracing or marking edges of the wheels 11 and 25 will simultaneously mark the lines or slight depressions 40 and 41 in the faces of the frame 35, as clearly indicated in Figs. 1 120 to 130

and 3 of the drawings. To mark the corresponding face portions of the door 36, the body of the tool or implement is now reversed, its guiding portion 5 being slid along the corner edge 42 of the door, and the marking or tracing wheels 11 and 25 will in a like manner respectively produce the traces or marks 43 and 44 in the door, as clearly indicated in said Figs. 1 and 4 of the drawings. Thus it will be seen that only two of the said rods and marking wheels or disks located in planes at right angles to each other in this case are necessary when the face of the door is flush with the face of the frame. When, however, the door is to be let in, as indicated in Figs. 2, 5, and 6 of the drawings, then it will be necessary to use the three rods and their tracing wheels or disks in the manner to be presently described. Referring now to Fig. 5, the device is first used in the manner herein set forth for producing, by means of the wheel or disk 25, the mark 44, a slight mark 45 being also made by the disk or wheel 11, which mark, however, is disregarded by the carpenter. The device is then reversed, so as to bring its guide portion 4 against the edge of the door-frame, as shown, and with the wheel or disk 10 of the previously-adjusted rod 8 the proper mark 46 is made. Having located the marks 44 and 46 by means of the disks or wheels 12 and 25 of the rods 9 and 10, the marks 47 and 48 are made in the faces of the door, as shown in Fig. 6 of the drawings, and in precisely the same manner as previously described.

From the foregoing of my present invention it will be seen that I have devised a simple and readily-manipulated tool or implement or a gage for tracing or marking lines upon work and which is especially adapted as a butt-gage, supplied with tracers or markers which can be used to work up closely to or flush with the door-casing where nailed to the jamb, and as the tracers or markers roll while cutting the edge of the chisel will enter a clean and straight mark, as it cannot follow any diagonal or cross grain in the wood marked. The tool or implement may also be used to mark with one gaging the depth and width of a rabbet, and it may be used also to gage the width and distance from the edge of the stuff of any ordinary mortise and tenon, as in cabinet and other work.

Since the marking edges of the several tracing or marking wheels or disks are sharp, they will cut while rolling and may be used to cut edges of plowing or grooving for inlay and other similar work, and finally the tool or implement may be used in various other ways and as any ordinary gage.

I claim—

1. A tracing or marking implement comprising a main body provided with an enlarged portion and a narrow portion extending therefrom, said enlarged portion and narrow portion producing offsets forming a longitudinally-extending guide upon each side of the said main body, said portions being provided with a pair of longitudinally-extending guiding-holes, said wide portion being provided also with a single and laterally-extending hole, said laterally-extending hole being arranged in a plane at right angles to the planes of the said longitudinally-extending holes, a rod slidably arranged in each longitudinally-extending hole, a tracing or marking wheel on each rod, the marginal edge of the one wheel extending beyond one edge of said narrow portion, and the marginal edge of the other wheel extending beyond the other edge of said narrow portion, a rod slidably arranged in said laterally-extending hole, and a tracing or marking wheel on said rod, the marginal edge of said wheel extending beyond one of the marginal edges of said enlarged portion, substantially as and for the purposes set forth. 75

2. A tracing or marking implement comprising a main body provided with an enlarged portion and a narrow portion extending therefrom, said enlarged portion and narrow portion producing offsets forming guides, said portions being provided with a pair of longitudinally-extending guiding-holes, said wide portion being provided also with a single and laterally-extending hole, said laterally-extending hole being arranged in a plane at right angles to the planes of the said longitudinally-extending holes, a rod slidably arranged in each longitudinally-extending hole, a tracing or marking wheel on each rod, the marginal edge of the one wheel extending beyond one edge of said narrow portion and the marginal edge of the other wheel extending beyond the other edge of said narrow portion, a rod slidably arranged in said laterally-extending hole, and a tracing or marking wheel on said rod, the marginal edge of said wheel extending beyond one of the marginal edges of said enlarged portion, and set-screws for securing said rods in their fixed and adjusted positions, substantially as and for the purposes set forth. 100

In testimony that I claim the invention set forth above I have hereunto set my hand this 3d day of March, 1906. 115

ALBERT E. JONES.
